(57) **CLAIM**

The ornamental design for a space shuttle play structure, as shown and described.

DESCRIPTION

FIG. 1 is a perspective view of the space shuttle play structure;

FIG. 2 is a top plan view of the space shuttle play structure of FIG. 1;

FIG. 3 is a front plan view of the space shuttle play structure of FIG. 1;

FIG. 4 is a rear plan view of the space shuttle play structure of FIG. 1;

FIG. 5 is a plan side view of the space shuttle play structure of FIG. 1; and,

FIG. 6 is a plan side view of the space shuttle play structure of FIG. 1.

The broken line showing of environment is for illustrative purposes only and forms no part of the claimed design.
